UNITED STATES PATENT OFFICE.

EDWARD ERNEST ROGERS, OF HIGHFIELD, FOUR OAKS, ENGLAND.

SAFETY-RAZOR.

1,072,506.

Specification of Letters Patent.

Patented Sept. 9, 1913.

Application filed March 29, 1912. Serial No. 687,126.

To all whom it may concern:

Be it known that I, EDWARD ERNEST ROGERS, a subject of the Kingdom of Great Britain, residing at Highfield, Lichfield

5 Road, Four Oaks, in the county of Warwick, England, have invented a certain new and useful Improved Safety-Razor, of which the following is a specification.

This invention comprises a new or improved safety razor and is particularly applicable to those of the type in which the blade holders are pivoted to rock for stropping purposes or to swing over for the removal of the blade.

10 It is the practice when using an ordinary razor to lather the face twice and to place the opposite sides of the blade against the face when removing the different lathers.

The present invention comprises a safety 20 razor operable substantially on the system of an ordinary razor *i. e.* a safety razor both sides of the blade of which may be used, from which it will be understood that in addition to the life of the blade being 25 doubled the result obtainable by the use of a safety razor according to the present invention is equal, or considering the facilities afforded by razors of the safety type, in excess of that previously obtainable only 30 by the use of an ordinary razor and a skilled operator.

According to the present invention two blade guards or shields are provided one on each side of the handle and the blade holder 35 is pivoted so that it can be made to readily occupy the relative position to either of the guards.

In order that this invention may be clearly understood and more easily carried 40 into practice reference may be had to the appended sheet of drawings, upon which:—

Figure 1 is a part sectional elevation of a safety razor according to the present invention. Fig. 2 is a plan of a blank from 45 which a part of the razor is formed. Fig. 3 is a side elevation of the member formed from the blank shown in Fig. 2. Fig. 4 illustrates a method of pivoting the blade holder to its supporting stem.

50 In a convenient embodiment of this invention, such as is illustrated by Figs. 1 to 4 of the drawings a frame member A the ends of which are shaped and bent to form blade guards a^1 and a^2 is mounted upon or secured to a tubular handle b conveniently by means 55 of a socket d which may be secured to the

handle and member A in any convenient manner, while slidably mounted within the handle is a plunger or piston b^1 from which extends a stem c^1 screwed to the plunger d , 60 carrying the blade holder hinge member d^1 having a stem or pintle e secured therein and supporting the blade holder D. To permit of the blade g being disengaged from the projections a^3 or a^4 and swiveled into 65 engagement with the projections on the other guard the extremities of the shaft e are adapted to project into elongated apertures a^5 formed in the side wings a^6 of the member A and a spring h is provided within 70 the handle b . By pressing upon the projecting extremity of the plunger b^1 the blade holder may be displaced to an extent depending upon the length of the apertures a^5 and the blade released from the projections 75 a^3 or a^4 and swiveled around the pivots e into operative relation to the other guard, when by releasing the plunger the spring causes the plunger and stem to assume the position shown in Fig. 1 in which position 80 the blade will be engaged by one or the other sets of projections a^3 or a^4 , which may be conveniently formed from substantially V-shaped strips of metal partially cut from near the extremities of the guards and bent 85 up as shown in Figs. 2 and 3. A stop b^2 may be formed upon the extremity of the plunger b^1 to limit its length of travel while the member A may be perforated as for instance in the manner shown in Fig. 2, while 90 if desired an armed member d^2 Fig. 4 may be employed in place of or in addition to the hinge member d^1 which serves to connect the blade holder e^1 to the stem c^1 .

The screw connection between the plunger 95 b^1 and the stem c^1 aforesaid is of advantage in that it allows the length of the latter to be adjusted.

What I claim as my invention and desire 100 to secure by Letters Patent is:—

1. In a safety razor, a frame including a pair of arms provided with opposed slots, a blade holder provided with a shaft rotatably and slidably mounted in said slots, a guard extending from said frame and provided with hook teeth adapted to engage over the edge of a blade held in said holder when the shaft is in one position in said slots, and means to move the shaft to a second position in said slots and release said 110 blade.

2. In a safety razor, a hollow handle, a

frame mounted on said hollow handle and having an opening therein registering with the opening in the handle, said frame including a pair of arms provided with opposed slots, a plunger extending through the opening in the frame into said handle, a hinge member carried by said plunger, a shaft passing through said hinge member and having its ends held in said slots, a 5 blade holder mounted on said shaft, a guard extending from said frame and provided with means to engage and hold a blade edge when in the holder with the plunger drawn into the handle, and means to move said 10 plunger in said handle.

3. In a safety razor, a hollow handle, a frame mounted on said hollow handle and having an opening therein registering with the opening in the handle, said frame including a pair of arms provided with opposed slots, a plunger extending through the 15 opening in the frame into said handle, a 20

hinge member carried by said plunger, a shaft passing through said hinge member and having its ends held in said slots, a 25 blade holder mounted on said shaft, a guard extending from said frame and provided with means to engage and hold a blade edge when in the holder with the plunger drawn into the handle, and means to move said 30 plunger in said handle, comprising a member slideable in the handle and projecting from the lower end thereof, a stem connecting said plunger and last mentioned member, and a spring surrounding the stem and 35 bearing at one end against the frame and at the other end against the member.

In witness whereof I have hereunto set my hand in the presence of two witnesses.

EDWARD ERNEST ROGERS.
